UNITED STATES PATENT OFFICE.

EDWARD H. JEEVES, OF LONDON, ONTARIO, CANADA.

WINDOW-SCREEN-ATTACHING DEVICE.

1,120,390.

Specification of Letters Patent.

Patented Dec. 8, 1914.

Application filed December 19, 1913. Serial No. 807,672.

To all whom it may concern:

Be it known that I, EDWARD H. JEEVES, of the city of London, Province of Ontario, Canada, have invented certain new and useful Improvements in Window-Screen-Attaching Devices, of which the following is a specification.

This invention relates to means for securing in place the detachable window screens, now ordinarily employed, in such a manner that the window sash beneath which the screen is used, may be closed when desired without the necessity of removing the screen from the window.

I attain my object by means of certain constructions and arrangements of the screen and the attachments which may be briefly described as follows: A flanged metal strip is secured to each side of the screen, the flange extending from bottom to top of the screen at an angle to the plane of its surface. Each strip is notched at its lower end to hook into a keeper secured to and behind one of the stops of the window frame. On these keepers the screen may swing to bring its upper end into or out of position below the window sash.

A hook is secured at the back of the stop in a suitable manner to be engaged by the flange of the strip on the screen to limit the outward swing of the latter. The keeper and hook are preferably formed from the same metal strip which is suitably shaped to be secured to the stop.

The invention is illustrated in the accompanying drawings in which—

Figure 1 is a front elevation of a window provided with a screen having my attaching devices; Fig. 2 a side elevation on an enlarged scale showing the attachments; Fig. 3 a front elevation of part of the same; Fig. 4 a perspective detail of the metal strip connected with the sides of the screen; and Fig. 5 a perspective detail of the plate connected with the sides of the window frame.

In the drawings like letters of reference indicate corresponding parts in the different figures.

1 is a wire fly screen of the ordinary extension type. 50

2 are the stops of the window frame between which the sashes slide. Each side of the screen is provided with an attachment comprising a metal strip 3 of substantially triangular form as shown, which strip is 55 provided with a flange 4. The metal strip is connected with the edge of the screen so that the flange is inclined to the plane of the surface of the screen. The screen is fitted between two of the stops 2 so that it 60 may be swung on its lower end to bring its upper end to a position below the adjacent window sash. When the screen is pushed from below the sash the latter may be lowered to the bottom. When the screen is 65 swung in and the sash is resting on its top the flanges 4 fit against the outer faces of the stops 2 effectually closing any gap which might otherwise exist between the sides of the screen and the stops. The flanges also 70 serve to limit the inward movement of the screen.

Suitable pivotal connections are formed between the lower ends of the screen and the window frame by means of the following 75 constructions: The strip 3 is split at the angle between the strip and the flange 4 to form the lower end of the latter as a downwardly projecting tongue 5. A keeper with which the tongue may engage is connected to 80 lie behind the adjacent stop 2. Preferably this keeper is formed in the following manner: A plate 6 L-shaped in cross-section is secured against the inner side and back of the stop. Near the lower end a transverse 85 cut 7 is formed in the back of the plate 6, and the metal below the cut is sprung outwardly to space it somewhat from the stop. This enables the tongue 5 of the adjacent metal strip to be inserted through the slit 7. 90 The lower part of the plate 6 thus forms a keeper 8 for the tongue 5.

In order that the tongue 5 should not be too long I preferably extend a cut 9 part-way down from the cut 7 at the angle of the 95 plate. The upper part of the keeper 8 thus

is free at both sides so that it may be sprung out as much as may be necessary to enable the tongue 5 to pass in behind it. It is necessary also to provide a stop of some kind to limit the outward swing of the screen on one or both of the plates 6. I therefore provide a hook 10 which hook is preferably formed of a tongue integral with the plate 6 above the keeper 8 and bent to form a hook directed toward the screen but lying entirely behind the stop. When the screen is swung outwardly, the flange 4 contacts with this hook as shown particularly in Fig. 2.

It should be specially noted that both the keeper 8 and the hook 10 are located entirely behind the stop so that the window opening is entirely clear and these parts are thus located where they are least likely to be damaged.

To insure the connection of the metal strips 3 to the screen being strong enough and to assist in properly positioning the same, I provide each of the metal strips 3 with a flange 11 oppositely directed to the flange 4. This flange lies flush against one of the surfaces of the screen and the fastenings securing the strip to the screen may be passed through this flange, though it is preferable also to drive some of the fastenings through the body of the strip.

The advantages of the specific attaching means employed should not be lost sight of. Four pieces only are required, two for attachment to the screen and two for attachment to the window frame. The parts attached to the screen extend continually from top to bottom leaving no gaps or openings at any point. The attachments to the window frame leave the window opening absolutely unobstructed. The parts all being constructed of metal stampings are exceedingly cheap and may be made with absolute accuracy so that all parts are interchangeable.

What I claim as my invention is:—

1. The combination of a window frame and sash; a screen fitted between side members of the window frame out of alinement with the sash, and swingable between said members to bring its upper end into or out of position below said sash; metal strips secured to the ends of the screen and each provided with a flange adapted, when the screen is swung to a position below the sash, to engage the outer side of one of the window frame members aforesaid; and a hook secured to the window frame limiting the outward swing of the screen.

2. The combination of a window frame and sash; a screen fitted between side members of the window frame out of alinement with the sash; metal strips secured to the ends of the screen each provided with a laterally extending flange terminating in a downwardly extending tongue; and a keeper

behind and secured to each of the aforesaid side members with which said tongues may be engaged to form pivots on which the screen may be swung to or from a position with its upper end below the sash and the said flanges engaging the outer sides of the window frame members aforesaid.

3. The combination of a window frame and sash; a screen fitted between side members of the window frame out of alinement with the sash; metal strips secured to the ends of the screen each provided with a laterally extending flange terminating in a downwardly extending tongue; and a keeper behind and secured to each of the aforesaid side members with which said tongues may be engaged to form pivots on which the screen may be swung to or from a position with its upper end below the sash and the said flanges engaging the outer sides of the window frame members aforesaid, said keepers each comprising a flat plate spaced from and suitably secured to one of the said window frame members.

4. In a window screen attaching device; a metal strip for attachment to the end of a window screen triangular in shape and provided along one edge with a flange substantially at right angles to the plate, the strip being slit at the narrow end to form a tongue of the lower end of the flange in combination with a part for attachment to a stop of the window frame comprising a metal plate L-shaped in cross-section adapted to fit the face and back of a stop and cut transversely to form at its lower end a flat plate or keeper and adjacent its upper end provided with a flat hook integral with the plate at the same side as the keeper and directed toward the angle of the plate.

5. In a window screen attaching device; a metal strip for attachment to the end of a window screen triangular in shape and provided along one edge with a flange substantially at right angles to the plate, the strip being slit at the narrow end to form a tongue of the lower end of the flange.

6. In a window screen attaching device; a metal strip for attachment to the end of a window screen triangular in shape and provided along one edge with a flange substantially at right angles to the plate the strip being slit at the narrow end to form a tongue of the lower end of the flange, the opposite edge of the plate being also formed with a flange extending in an opposite direction to the first mentioned flange.

7. In a window screen attaching device; a part for attachment to a stop of the window frame comprising a metal plate L-shaped in cross-section adapted to fit the face and back of a stop and cut transversely to form at its lower end a flat plate or keeper and adjacent its upper end provided with a

flat hook integral with the plate at the same side as the keeper and directed toward the angle of the plate.

8. In a window screen attaching device;
5 a part for attachment to the top of a window frame comprising a metal plate L-shaped in cross-section, slit across the back near the lower end and partway down from the slit to the end at the angle of the plate to form
10 a keeper, a hook being formed integral with

the free edge of the back above the keeper, the hook being spaced from the back and directed toward the side of the back adjacent the angle of the plate.

Signed at Toronto, Ontario, Canada, this 15
8th day of December, 1913.

EDWARD H. JEEVES.
